UNITED STATES PATENT OFFICE.

GEORGE Y. SMITH, OF MINNEAPOLIS, MINNESOTA.

ARTIFICIAL-FUEL PRESS.

SPECIFICATION forming part of Letters Patent No. 430,701, dated June 24, 1890.

Application filed April 28, 1890. Serial No. 349,815. (No model.)

To all whom it may concern:

Be it known that I, GEORGE Y. SMITH, a citizen of the United States, residing at Minneapolis, in the county of Hennepin and State 5 of Minnesota, have invented certain new and useful Improvements in Artificial-Fuel Presses; and I do hereby declare the following to be a full, clear, and exact description of the invention, such as will enable others 10 skilled in the art to which it appertains to make and use the same.

My invention relates to machines for pressing artificial fuel into bricks or blocks. To practically utilize the waste inflammable substances—such as the immense piles of coal-dross, culm, or slack—and present the material in proper form for use as fuel, machinery of various kinds has been devised.

The object of my invention is to improve 20 heretofore-existing devices and to produce a machine in which the material can be agglomerated into blocks under great pressure, so that it will burn evenly and will not disintegrate even when employed in furnaces 25 having a forced draft, such as are common in locomotives. With this end in view I construct a suitable frame-work, in which are mounted revoluble wheels spaced several feet apart and each provided with a series of 30 molds of any desired form, each mold containing a discharge-piston. Each wheel rotates around a stationary shaft provided with a cam which is so located that it will at the proper time force the pistons outward to dis- 35 charge the completed bricks or blocks from the molds. Between the wheels I place a hydraulic press or other suitable device which will cause two pistons to move outward in opposite directions simultaneously and thereby 40 enter a mold of each wheel, which is in line with the pistons, and press the material therein into the desired form. I contemplate the arrangement of a series of mold-wheels side by side in the same frame and of a cor- 45 responding number of sets of pistons between the wheels, so that a series of bricks or blocks can be synchronously formed. Gearing and a clutch mechanism are employed, whereby an intermittent rotation will be given the 50 mold-wheels, and each wheel is locked when

a mold is in line with a piston by an automatically-acting device, which will be hereinafter fully described. Mounted over each wheel is a hopper containing the material to be formed into bricks or blocks, and within 55 the hopper is a screw or other force-feed device. At one side of and below each hopper is a wheel provided with a series of pressing-surfaces, one of which enters each mold after it has been filled from the hopper and im- 60 parts a preliminary pressure to the contents thereof.

Any form of mechanism necessary to impart a synchronous motion in opposite directions to the pressing-pistons may be placed 65 between the wheels, and I have shown a hydraulic press, a right and left hand screw, and a toggle-joint as some of the devices which can be advantageously employed, although it is obvious that other systems of levers or a 70 steam-actuated press could be used with equal facility.

In the accompanying drawings, in which like numerals are placed on like parts throughout the several views, Figure 1 is a partial 75 longitudinal vertical section of a preferred form of my invention. Fig. 2 is a partial transverse section of a double machine. Figs. 3, 4, 5, and 6 are detail views hereinafter referred to, and Figs. 7 and 8 are views of 80 modifications hereinafter described.

1 is the frame of the machine, provided with supporting-legs 2.

3 are hoppers attached to the frame.

4 are shafts, each carrying a spiral feed- 85 plate 5.

6 are bevel-gears on shafts 4, intermeshed with like gears 7 7 on a shaft 8, provided with a driving-pulley 9.

1^x 1^x are standards rising from the frame, 90 in which the shaft 8 is journaled.

10 10' are wheels, each provided with a se- 95 ries of molds 11, and 12 12 are pistons seated in the molds, each having a stem 12^x.

13 13' are shafts fixed in pillow-blocks of 95 the frame, and 14 14' are stationary cams se- cured to said shafts.

15 is the driving-shaft of the machine, pro- 100 vided with a spur-gear 16 at one end and with a suitable half-clutch 17 at the other.

- 18 is a sleeve on shaft 15, having a spline 19, and 20 is the movable part of the clutch, movable back and forth on the spline and sleeve.
- 5 21 is a power-pulley fixed on the sleeve.
- 22 is a gear intermeshing with gear 16, and 23 is a second gear in mesh with a large gear 24 on a hub attached to wheel 10.
- 25 is a gear in mesh with driving-gear 16 and also with a large gear 24' on the hub of gear 10'.
- 26 is a part of the frame-work in which the shafts of the gears 16, 22, 23, and 25 are journaled.
- 15 27 27^x are wheels carried by the shafts of gears 23 25, respectively, and provided with surfaces 28, which successively enter the molds and impart a preliminary pressure to the material just after each mold has been 20 filled from the hopper.
- 29 is a hydraulic press of any approved pattern, which is mounted on the frame, and 30 is a pump for forcing liquid to such press.
- 31 is a supply-pipe for the pump, leading 25 to a suitable tank or other liquid-reservoir.
- 32 is the pipe leading from the pump to the press, and 34 are eccentrics for operating the pump, mounted on a shaft 35, having a driving-pulley 36 and loose pulley 36'.
- 30 37 38 are pistons of the press, provided with pressing-plungers 39 40, respectively, of a size proper to enter the molds of the wheels.
- 41 and 42 are projections depending from the pistons, and 43 44 are cords passing over 35 sheaves 45 46 and attached to a weight 47, which tends to pull the pistons within the press.
- 48 is the passage for the escape of liquid from the press, and 49 is a valve held up by 40 a cup 50.
- 51 is a three-armed lever pivoted beneath the press, the short arm 52 of which bears against a projection on the under side of the cup 50, while its long arm 53 is equipped with 45 an adjustable weight 54, which can be set to permit the desired pressure to be given the pistons of the press.
- 51^x is a bar connecting the depending arms 56 of the levers 51 when a series of wheels 50 and presses is employed.
- 56^x is a pair of nippers pivoted on the side of the press, and 57 is a spring which tends to keep the jaws thereof closed.
- When the pistons are withdrawn within 55 the press, projections 58 strike the long arms of the nippers and cause the jaws thereof to open, as shown in Fig. 5; but as soon as the pistons begin to move away from each other spring 57 immediately closes said jaws, and 60 they will then be in position to catch and retain the long arm 53 of lever 51 when it is raised by the pressure of liquid against cup 50. In order that the pistons may act with accuracy when a mold on each wheel is 65 in line with each of them, it is necessary to stop the driving-gearing and to lock the
- wheels against all possibility of movement during the pressing operation. In order to accomplish this result, I have devised an automatically-acting clutch and lock mechanism, which will now be described.
- Each mold-wheel is provided on its outer side with a laterally-projecting rim 10^x, in which is formed a series of open notches 59 59, one for each mold. Attached to each piston is an arm 37^x 38^x.
- 60 is a horizontal extension or platform projecting from the press in the single machine, as shown in Figs. 3 and 4.
- 61 61' are brackets or standards on the 80 platform.
- 62 62' are bell-crank levers, each provided with a lug 62^x, pivoted at 63 63' to the respective brackets.
- 64 64' are dogs pivoted to the levers, and 85 65 65' are springs, one for each dog.
- 66 66' are locking plungers or latches articulated to the levers 62 62' and movable through housings 67 67' on the extension 60.
- 68 is a guideway on extension 60 for two 90 bars 69 69', attached by fixed bolts, respectively, to the arms 37^x 38^x and provided with cam-shaped lugs 69^x 69^x.
- 70 70' are toggle-links articulated to the bars 69 69'.
- 71 is a slide connected to the toggle-links and movable in a guide 72, having an open slot 72^x.
- 73 is a pin capable of a vertical movement in the slide 71, said pin being threaded at its 100 lower end and provided with a nut 74. (See Fig. 2.)
- 75 is a chamber cored out of the frame-work beneath guide 72 and having a curved upper wall 75^x.
- 76 is a platform resting on spring 77, which presses it against pin 73.
- 78 is a bracket projecting from the frame, in which is pivoted a lever 79, connected with the movable part 20 of the clutch.
- 80 is a spring connected with an arm of the bracket and with the clutch-lever and normally tending to throw the clutch out of engagement.
- 81 is a lug, and 82 a spring-pressed pivoted 115 dog on lever 79.
- 89 is a carrier-belt located below the wheels.
- Having described this form of my invention, the operation thereof is as follows: Material to be molded into condition suitable 120 for fuel is placed in the hoppers and is intermixed and at the same time fed downward by the feed-screws therein, thereby filling the mold cavities or pockets in each wheel that are beneath the hopper. The pump is then started and the pistons 37 38 are forced in opposite directions until the pressure is sufficient to force downward relief-valve 49 and cup 50 against the action of weighted lever 51. As the valve descends, the lever 51 will 125 turn on its pivot, thereby raising its long arm (carrying weight 54) from the position

shown in Fig. 5 in full lines to that represented by dotted lines in the same figure and permitting the barbed jaws of the nippers to snap behind said arm and hold the weight 5 temporarily in an elevated position. The pistons are now pulled within the cylinder by cords 43 44 and weight 47, and in their retrogression arms 37^x 38^x cause the bars 69 69' to actuate the toggles 70 and 70' and force 10 slide 71 outward, and the lugs 69^x 69² come against the pivoted cams 64 64', which are prevented from tipping by lugs 62^x, and withdraw the locking-plungers 66 66' from the notches 59, and thereby release the wheels. 15 As slide 71 moves outward through guide 72 it carries the vertically-movable pin 73 with it, and said pin being in contact with dog 82 it forces the pivoted lever 79 to throw clutch-half 20 into engagement with the fixed half 20, thus starting the machine, and, through the intermediate gearing, rotating the mold-wheels a distance just sufficient to bring another set of filled molds into alignment with the pistons. The extent of rotation of the 25 mold-wheels is governed by the movement of the pin 73 in the chamber 75 and slot 72^x, for as said pin traverses the same it is gradually withdrawn by the curved wall 75^x until its end leaves the dog 82 and permits spring 80 30 to exert its power and tilt lever 79 to throw the clutch out of action. It is to be understood that as soon as cam-lugs 69^x 69² leave the pivoted dogs 64 64' the springs 65 and 65' force pivoted levers 62 62' downward and 35 cause them to throw the locking-plungers against the plain portions of the rims of the wheels between the notches in readiness immediately to snap into the notches as soon as they arrive opposite the plungers, and 40 thereby lock the wheels in position. On the return of slide 71 to its original position pin 73 will tilt dog 82 on its pivot without actuating lever 79, and the cam-lugs 69^x 69² also act in the same manner on dogs 64 64' when 45 the pistons move outward and it is not desired to actuate the locking-plungers. As the wheels rotate intermittently, the fixed cams force outward the pistons and cause them to discharge the bricks upon the carrier-belt 89. 50 In the modification represented in Fig. 7 the pistons are shown as actuated by a right-and-left screw 83, driven by a suitable gear 84, the screw engaging with nuts in the pistons.

55 In Fig. 8 the pistons are represented as actuated by a toggle-joint 85 86, connected to a plunger 87, movable in a guide 88 in the frame.

In the double arrangement represented in 60 Fig. 2 levers 51 are represented as connected by a link 51^x, so that if the pressure in one cylinder should be greater than that in the other both relief-valves will be synchronously released. In the double arrangement the 65 bed-plate is extended and the pump placed thereon between the cylinders, and it is con-

nected by branch pipes 32^x with each cylinder. The wheels are also suitably connected together to revolve in unison.

It is obvious that many changes could be 70 made in the construction of the apparatus without departing from my invention, and that the details of the gearing and stop and clutch-actuating mechanism could be widely varied. Other forms of stopping and starting mechanism could also be advantageously employed.

It is obvious that my machine may be employed for pressing other materials than those mentioned, and that any kind of well-known feed device can be placed in the hoppers as a substitute for the spiral blade shown and described.

It is also obvious that wheels containing a single mold or a less number of molds than 80 those shown and described could be advantageously employed with plungers of a larger size, so that large blocks of material could be formed in the manner clearly indicated.

In practice, when the hydraulic press is 90 used intermediate the wheels, the liquid will be pumped from and discharged into a suitable tank located beneath the frame-work, which it is deemed necessary to illustrate.

Having thus described my invention, what 95 I claim is—

1. A machine for pressing material, comprising revoluble mold-wheels and plungers between said wheels movable synchronously in opposite directions, substantially as and for 100 the purpose specified.

2. A machine for pressing material, comprising revoluble mold-wheels, plungers between said wheels, and a device for forcing the plungers outward synchronously, substantially as and for the purpose specified.

3. A machine for pressing material, comprising intermittently-revoluble wheels, each provided with a series of molds or pockets, plungers between said wheels movable synchronously in opposite directions, and discharge-pistons in the molds, substantially as and for the purpose specified.

4. A machine for pressing material, comprising revoluble mold-wheels, pressing-plungers located between the wheels and movable synchronously in opposite directions, gearing connecting said wheels, and mechanism for actuating the plungers and for automatically stopping and starting the gearing, substantially as and for the purpose specified.

5. A machine for pressing material, comprising revoluble mold-wheels spaced some distance apart, a hopper for the material located over each wheel, a feed device in the 125 hopper, and pressing-plungers located between the wheels and movable synchronously in opposite directions, substantially as and for the purpose specified.

6. A machine for pressing material, comprising revoluble mold-wheels, gearing connecting said wheels, and pressing-plungers

movable synchronously in opposite directions, located between the wheels, substantially as and for the purpose specified.

7. A machine for pressing material, comprising revoluble mold-wheels, a cylinder located between said wheels, and pistons carrying pressing-plungers in said cylinder, substantially as and for the purpose specified. 70

8. A machine for pressing material, comprising revoluble mold-wheels, a hydraulic cylinder between said wheels, pistons in said cylinder, each carrying a pressing-plunger, and a pump for forcing liquid into the cylinder, substantially as and for the purpose specified. 75

15 9. A machine for pressing material, comprising revoluble mold-wheels, a cylinder between the wheels, a pipe for conveying the motive fluid to the cylinder, and pistons having pressing-plungers mounted in the cylinder and movable synchronously in opposite directions, substantially as and for the purpose specified.

10. A machine for pressing material into 25 the forms of bricks or blocks, comprising revoluble mold-wheels, a cylinder located between the wheels, a pipe for conveying the motive fluid to the cylinder, pistons movable in opposite directions, a relief - valve, and 30 means for withdrawing the pistons within the cylinder, substantially as and for the purpose specified.

11. A machine for pressing material into 35 the form of bricks or blocks, comprising a pair of revoluble mold-wheels, pressing-plungers between said wheels, movable synchronously in opposite directions, mechanism for locking the wheels when a mold in each is in alignment with the pistons, and mechanism 40 for intermittently revolving the wheels, substantially as and for the purpose specified.

12. A machine for pressing material, comprising revoluble mold-wheels, plungers between said wheels, and clutch and locking devices actuated by the plungers, substantially as and for the purpose specified. 45

13. A machine for pressing material, comprising revoluble mold-wheels, a cylinder located between the wheels, pistons in said cylinder movable synchronously in opposite direction, and a weight for withdrawing the pistons within the cylinder, substantially as and for the purpose specified. 50

14. A machine for pressing material, comprising revoluble mold-wheels, gearing for revolving the same, a hopper over each wheel containing a suitable device for forcing material into the molds, a device for imparting a preliminary pressure to the material in each mold, and pressing-plungers movable synchronously in opposite directions, substantially as and for the purpose specified. 60

15. In a machine for pressing material, the combination, with the mold-wheels and pressing-plungers located between said wheels, of

a driving-shaft, a clutch, and intermediate devices connecting the plungers and clutch, substantially as and for the purpose specified. 70

16. In a machine for pressing material, the combination, with the revoluble mold-wheels and intermediate pressing - plungers, of a driving-shaft, a clutch in two halves thereon, a clutch-shipping lever, and devices intermediate the plungers and driving-shaft for actuating said lever, substantially as and for the purpose specified. 75

17. A machine for pressing material, comprising a series of mold-wheels located adjacent to each other and a series of sets of pressing-plungers, each set movable synchronously in opposite directions, substantially as and for the purpose specified. 80

18. In a machine for pressing material, the combination, with revoluble mold-wheels, each provided with a series of notches, of pressing-plungers located between the wheels, and latches actuated by the plungers to lock the wheels in position during the pressing operation, substantially as and for the purpose specified. 85

19. In a machine for pressing material, the combination, with a driving-shaft, revoluble mold-wheels geared with said shaft, and pressing - plungers intermediate the wheels, of latches for locking the wheels, actuated by the plungers, and a clutch-lever and means for actuating the same, substantially as and for the purpose specified. 90

20. In a machine for pressing material, the combination, with revoluble mold-wheels and pressing-plungers intermediate said wheels, of locking-latches actuated by the plungers, substantially as and for the purpose specified. 95

21. In a machine for pressing material, the combination, with revoluble mold - wheels, each provided with a notched rim, of latches for engaging the notches in said rims, springs for actuating said latches in one direction, pressing - plungers, and devices connected therewith for withdrawing the latches, substantially as and for the purpose specified. 100

22. The combination, with a revoluble wheel, of mechanism for locking said wheel, consisting of a pivoted lever, a latch carried thereby, a pivoted dog, and a spring bearing against the dog, substantially as and for the purpose specified. 115

23. The combination, with revoluble wheels having notched rims, of pivoted levers, latches carried by said levers, a pivoted dog on each lever, and slide-bars provided with lugs for engaging the dogs, substantially as and for the purpose specified. 120

24. The combination, with the revoluble mold-wheels and pressing-pistons intermediate the same, of slide-bars connected to said pistons, a slide movable at right angles to said slide-bars and connected therewith, a pin vertically movable in the slide, a driving-

shaft, and a clutch-lever, substantially as and for the purpose specified.

25. In a machine for pressing material, the combination, with a driving-shaft, of a clutch-
5 actuating lever and a slide-bar provided with a movable pin for operating said lever, substantially as and for the purpose specified.

In testimony whereof I affix my signature in presence of two witnesses.

GEORGE Y. SMITH.
